US0D1113079S

(12) United States Design Patent (10) Patent No.: US D1,113,079 S
(45) Date of Patent: * Feb. 17, 2026

(54) APPAREL

(71) Applicant: NIKE, Inc., Beaverton, OR (US)

(72) Inventor: Sydney Gayda Kehoe, Portland, OR (US)

(73) Assignee: NIKE, Inc., Beaverton, OR (US)

() Term: 15 Years

(21) Appl. No.: 29/972,262

(22) Filed: Nov. 8, 2024

(51) LOC (15) Cl. 02-02

(52) U.S. Cl.

USPC D2/717

(58) Field of Classification Search

USPC D2/717, 840, 847, 849, 742, 731

CPC A41B 1/00; A41B 1/08; A41B 1/10

See application file for complete search history.

(74) Attorney, Agent, or Firm — Banner & Witcoff, Ltd.

(57) CLAIM

The ornamental design for an apparel as shown and described.

DESCRIPTION

FIG. 1 is a front view of an apparel showing my new design; FIG. 2 is a front left perspective view thereof; FIG. 3 is a front right perspective view thereof; FIG. 4 is a front view of an apparel showing an alternative embodiment of my new design; FIG. 5 is a front left perspective view thereof; and, FIG. 6 is a front right perspective view thereof. The broken lines immediately adjacent to the shaded area define the bounds of the claimed design and form no part thereof. The broken lines depicting the remainder of the apparel form no part of the claimed design.

1 Claim, 6 Drawing Sheets
